UNITED STATES PATENT OFFICE.

FRANK H. STONER, OF MONROE, MICHIGAN, ASSIGNOR TO WILDER-STRONG IMPLEMENT CO., OF MONROE, MICHIGAN, A CORPORATION OF MICHIGAN.

LAND-ROLLER.

1,237,406.

Specification of Letters Patent. Patented Aug. 21, 1917.

Application filed October 16, 1916. Serial No. 125,898.

To all whom it may concern:

Be it known that I, FRANK H. STONER, a citizen of the United States of America, residing at Monroe, in the county of Monroe and State of Michigan, have invented certain new and useful Improvements in Land-Rollers, of which the following is a specification, reference being had therein to the accompanying drawings.

10 This invention relates to land rollers or the like and refers more particularly to an improved roller with which is combined a scraper for removing any clogs of dirt or other matter adhering to the surface of the roller.

15 Among the objects of the invention are to provide a land roller or the like with a scraper which will remove from the surface of the roller any clogs of dirt or other material; to so construct and arrange the scraper that it will operate irrespective of the direction of rotation of the roller; to provide a construction which can be economically manufactured and conveniently applied to rollers now in use; to provide 20 means for resiliently pressing the scraper toward the surface of the roller and means for preventing the springs from pushing the scraper toward the roller more than a predetermined distance; to provide a construction in which the handle of the roller can be utilized as a guide means for the scraper; and in general to provide a new and improved construction of the character 25 above referred to.

In the drawings:

Figure 1 is a top plan view, partly in section of a roller embodying my invention;

Fig. 2 is an end elevational view, partly 40 in section of the roller shown in Fig. 1;

Fig. 3 is an enlarged fragmentary perspective view of the scraper.

Describing in detail the construction shown in the drawings, A designates the 45 roller which at its opposite end is provided with bearings B and C to which is secured the handle ends D and E. While the handle construction could be of various forms, in the particular one illustrated the ends D and E are connected by a transverse portion F and the handle proper is formed in the shape of a U-shaped member G.

In order to prevent clogs of dirt or other matter adhering to the surface of the roller 50 and then interfering with the action, means

are provided for automatically scraping off from the surface of the roller any matter adhering thereto. In detail the scraper comprises an angle shaped bar H having transverse flanges H' and H² each of which are notched at J near the end. These notches fit over the end or side portions E and D of the handle and thus the latter serve as guides for the scraper while permitting the latter a relatively free movement toward and from the surface of the roller. It will be noticed that the flange H' has a scraping edge K' while the flange H² has a corresponding scraping edge K². Thus the same scraping action will take place irrespective of the direction of rotation of the roller.

In addition to being guided by the handle the scraper bar H is normally spring pressed toward the roller by springs M and M' sleeved upon studs N and N', which springs are interposed between the scraper plate and the transverse portion F of the handle. The studs N and N' are each provided with a threaded end O which is screwed into the angle bar H while the opposite ends project through apertures P and P' formed in the transverse portion H and are provided with adjustable wing nuts Q and Q'. This arrangement permits the operator, by tightening up the wing nuts to limit the amount of movement of the scraper bar toward the roller. Thus while the springs force the scraper yieldably toward the roller the two members can be kept apart by adjusting the wing nuts; this will prevent any unnecessary friction between the scraper and the roller.

While I have shown and described the invention as applied to what is known as a hand roller, it is not necessarily limited to this particular type of roller since it could be used with rollers having different shaped handles or tongues, and various other changes made in the details of construction within the scope of my invention.

What I claim as my invention is:

1. The combination with a roller, of a handle therefor, and a scraper for said roller, carried by said handle, and mechanism for spring pressing said scraper toward the surface of said roller and limiting the movement of said scraper toward said roller.

2. The combination with a roller, and a handle comprising spaced side portions pivotally connected to the roller, of a scraper

having a sliding engagement with said portions of the handle, and means for positioning said scraper with reference to said roller.

3. The combination with a roller and a handle therefor, comprising spaced side portions, of a scraper for said roller comprising an angle bar having its ends notched to fit over the side portions of the handle.

4. The combination with a roller, of a scraper therefor, comprising an angle bar having its flanges projecting toward the roller and arranged to act as a scraper for

said roller when the roller is turned in either direction.

5. The combination with a roller, of a scraper therefor, comprising an angle bar having its flanges projecting toward the roller and arranged to act as a scraper for said roller when the roller is turned in either direction, and means for adjusting said scraper with reference to said roller.

In testimony whereof I affix my signature.

FRANK H. STONER.
